ASH TRAY

August Belz, 13 Seestrasse, 9403 Goldach, Switzerland

Filed June 8, 1970, Ser. No. 23,355

Term of patent 14 years

Int. Cl. D27—03

U.S. Cl. D85—2

FIG. 1

FIG. 2

FIG. 4

FIG. 3

FIG. 5

FIG. 1 is a front perspective view of an ash tray embodying my new design;

FIG. 2 is a front perspective view showing the ash tray in an open position;

FIG. 3 is a rear perspective view showing the ash tray in a closed position;

FIG. 4 is a top plan view thereof; and

FIG. 5 is a bottom plan view thereof.

I claim:

The ornamental design for an ash tray, as shown.
